(57) **CLAIM**

The ornamental design for a trim for a light fixture, as shown and described

DESCRIPTION

This application is related to commonly assigned, concurrently filed application Ser. No. 29/252,131, the disclosure of which is hereby incorporated by reference herein.

FIG. 1 is an isometric view of the first embodiment of the trim for a light fixture of the present invention;

FIG. 2 is a front elevation view thereof;

FIG. 3 is a right-side elevation view thereof, the left-side elevation view being a mirror image thereof;

FIG. 4 is a rear elevation view thereof;

FIG. 5 is a top plan view thereof; and

FIG. 6 is a bottom plan view thereof.

FIG. 7 is an isometric view of a second embodiment; and, FIG. 8 is an isometric view of a third embodiment.

The broken line is included for the purpose of illustrating environmental structure and forms no part of the claimed design.
